UNITED STATES PATENT OFFICE.

CHARLES A. KETTERER, OF EAST ST. LOUIS, ILLINOIS.

REFRIGERATOR.

1,350,655.

Specification of Letters Patent. Patented Aug. 24, 1920.

Application filed July 11, 1918. Serial No. 244,395.

To all whom it may concern:

Be it known that I, CHARLES A. KETTERER, a citizen of the United States, and resident of East St. Louis, in the county of St. Clair and State of Illinois, have invented certain new and useful Improvements in Refrigerators, of which the following is a specification, containing full, clear, and exact description, reference being had to the accompanying drawings, forming a part thereof.

My invention relates to improvements in "refrigerator display boxes" and has for its primary object a display box in which is located an ice receptacle and a plurality of air tubes for supplying the box with a cold dry air. A further object is to provide the ice receptacle of a refrigerator display box with an air circulation regulating means, so that the circulation of air can be regulated according to the outside surrounding temperature.

In the drawings,

Figure 1 is a longitudinal section of a box with my device in position.

Fig. 2 a top view of the container lid, showing the circulation regulating valves or dampers.

Fig. 3 is a cross section of the ice and brine containers, showing the air circulating tubes and valves.

Fig. 4 is a top plan view of one of the short circulating tubes made use of.

Fig. 5 is a vertical sectional view of the same.

Fig. 6 is a section through the cover of the ice container, showing the lip opening extending into the air circulation tube with the valve or damper in section.

In carrying out my invention, I provide a refrigerator case 8 which is insulated from the outside atmosphere in any well known manner. Within the case I provide a section 9 in which the ice receptacle is located.

The portion 10 of the box is separated from the portion which contains the ice receptacle by means of a sheet of reticulated material 11 and a splash apron 12. The object of these are to prevent food stuffs from falling

into the compartment designed for the ice receptacle. In the bottom of the compartment 9, I place a drip pan 13, which is provided with the usual out-let pipe 14, so that the waste water may be carried away. The ice receptacle consists of a plurality of angle irons 15 to which is attached a bottom 16,

which has two of its sides sloping and the others being vertical, thereby forming a brine chamber or receptacle 17. In this chamber 17 are securely attached the long 60 air circulating pipes 18, which pipes extend upward through the ice chamber to the lid of the container, and the short pipes 19 extending only in the brine chamber. These air circulating pipes consist of the outer 65 pipe 20 and the intermediate pipe 21 and an inner pipe 22, the pipes 20 and 21 being separated from each other by means of a corrugated pipe 23, and the pipes 21 and 22 being separated with a similar corrugated pipe 70 24. The upper ends of the pipes 20 terminate at a point on the line with the upper edge 25 of the receptacle 17, the upper edge 26 of the pipes 21 terminating a short distance above the upper edge of the outer 75 pipes and the upper edge 27 of the center sections extend beyond the edge 26 of the pipe 21.

In the central section are a series of pipes 19 and located within the pipe 22 I provide 80 an X of wires 28 on which rests a washer 29, the object of which is to prevent the entrance of ice into the central tube 22. In the side or outer tubes 18, the central pipe 22 extends upwardly until it contacts with the lid 85 28 of the ice receptacle. This lid is provided with perforations 29a, the inner edges of which are bent downwardly to form a lip 30, which enters these extended tubes. Over the openings 29a and pivotally connected to 90 the lid, I mount valves or dampers 30a, these dampers being provided with a series of graduated openings 31 and a projection 32 by means of which the dampers can be moved, so as to regulate the opening for the 95 admission of air into the extending pipes 22.

Attached to the angle irons 15, I secure horizontal angle irons 33, on which rests a sheet of reticulated material 34. On the outside of the angle irons 15 are secured plates 100 35. These plates and the reticulated material form the ice chamber; there being a space between the ice chamber and the brine chamber, amounting to the thickness of the metal in the angle irons. This ice chamber 105 is filled with crushed ice and salt and the resulting brine is allowed to drip into the brine chamber 17. The circulation of air is shown by the arrows in Fig. 1, by which it will be readily seen as the air becomes warm 110 in the display chamber it rises and passes through the openings 29a and pipes 22 and

again becomes chilled. In the event that the air in the box becomes too dry, I provide a pair of S shaped gutters 36, which are hung over the vertical sides of the brine chamber and will allow frost to form on the lower portions of the brine chamber, thereby supplying a sufficient amount of moisture to the box.

The brine receptacle 17 is provided at its bottom with the valve 38, the purpose of which is to drain the brine from the receptacle and also to serve as an outlet when the receptacle 17 is being cleaned. The pipes 21 and 22 as well as the corrugated pipes 23 and 24 are prevented from sliding downward into the pipe 20 by means of a bar or rivet 37 extending through the pipe 20.

The operation of my device is as follows:

The ice chamber is filled with crushed ice and salt and the resulting brine allowed to drip through the openings in the reticulated bottom 34, until the brine chamber has become filled to its capacity. Any additional brine dripping into the receptacle 17 will overflow its sides, as well as enter the outer pipes 20. This brine will cut off or melt any congealed moisture which will form in the pipes or on the sides of the brine receptacle in the shape of frost. Some of the brine dripping through the reticulated sheet 34 will drip into and flow around the corrugated pipes 22 and 23 and cut off any congealed frost which may form thereon, and around the pipes 18 and 20. In the central pipes, the washer 29 will prevent small particles of ice from dropping therein, but at the same time allow brine to enter this pipe and cut off frost.

It has been found by the use of my device, that at times the box becomes too dry, in other words, cold air admitted does not contain sufficient moisture to keep the articles in the box in proper condition. When this is the case, I make use of the S shaped gutters 36 which will carry off the brine flowing over the vertical sides of the box, and allow frost to form on these vertical sides, thereby supplying my refrigerator with sufficient moisture. The amount of this moisture can be regulated by the length of the gutter or by putting the gutter on only one

side of the device. Whenever the flow of air through the box becomes too rapid, I may either close off the openings 29^a, which lead into the extended pipes 22 entirely, or by means of the graduated openings in the dampers, check this flow until the desired circulation has been reached. The central openings 29^a in the lid remain open at all times, but if found necessary these may also be provided with dampers without departing from the spirit of my invention.

Having fully described my invention what I claim is:

1. A refrigerator comprising a storage compartment, an air cooling compartment located adjacent thereto, air circulating tubes located in the cooling compartment and communicating with the storage compartments, slide valves for regulating the flow of air through the tubes, and means for removing the congealed moisture from the bottom of the cooling compartment.

2. A refrigerator comprising a storage compartment a refrigerator receptacle located adjacent thereto, said receptacle having an ice compartment and a brine compartment, the compartments being separated from each other by a screen, air circulation tubes extending through the ice and brine compartments, slide valves for regulating the passage of air through the tubes, and means for removing the congealed moisture from the tubes and ice receptacle.

3. A refrigerator comprising a storage compartment, a cooling compartment located adjacent thereto, tubes located in the cooling compartment having communication with the storage compartment, dampers having graduated openings for regulating a flow of air through the tubes, means for removing congealed moisture from the tubes and bottom of the cooling compartment, and means for regulating the amount of moisture supplied to the storage compartment.

In testimony whereof, I have signed my name to this specification, in the presence of a subscribing witness.

CHARLES A. KETTERER.

Witness:

W. C. STEIN.
